UNITED STATES PATENT OFFICE.

EDWIN C. CURTIS, OF KINGSTON, AND GEORGE E. REYNOLDS, OF WYOMING,
PENNSYLVANIA.

WINDOW SHADE AND CURTAIN FIXTURE.

Application filed August 20, 1924. Serial No. 733,191.

To all whom it may concern:

Be it known that we, EDWIN C. CURTIS and GEORGE E. REYNOLDS, citizens of the United States, residing, respectively, at 5 Kingston and Wyoming, in the county of Luzerne and State of Pennsylvania, have invented a new and useful Window Shade and Curtain Fixture, of which the following is a specification.

- 10 This invention aims to provide a novel means whereby a window shade roller, or a curtain, may be mounted on a window frame, without resorting to tacks, nails, screws or the like.
- 15 Another object of the invention is to provide novel means whereby the brackets may be adjusted along the holder, to accommodate shade rollers or curtain poles of different lengths.
- 20 It is within the province of the disclosure to improve generally and to enhance the utility of devices of that type to which the invention appertains.
- 25 With the above and other objects in view, which will appear as the description proceeds, the invention resides in the combination and arrangement of parts and in the details of construction hereinafter described and claimed, it being understood that 30 changes in the precise embodiment of the invention shown, can be made, without departing from the spirit of the invention.

In the accompanying drawings:—

Figure 1 shows in elevation, a portion of a window frame, whereunto the device forming the subject matter of this application has been applied; Figure 2 is an elevation showing the holder; Figure 3 is a plan showing the holder mounted on a portion of the window frame; Figure 4 is a cross section showing the curtain bracket on the holder; Figure 5 is a longitudinal section showing how the second bracket cooperates with the holder; Figure 6 is a perspective view showing the holder; Figure 7 is an elevation showing a modified form of bracket adapted to be used when a curtain pole is to be supported.

The device forming the subject matter of this application comprises a plate-like body 1, provided at one end with a flange 2 located at right angles to the body, the flange having any desired number of inwardly extended prongs 3, located approximately

parallel to the body. Notches 4 are fashioned at the point of juncture between the body 1 and the flange 2. The body 1 is distorted to form an inwardly extended longitudinal rib 5 and to form raised flanges 6 on each side of the rib. Transverse seats 7 are formed in the outer surfaces of the flanges 6. A prong 8 is struck from the rib 5 and extends inwardly about at right angles to the prongs 3.

The numeral 9 designates a bracket of any desired kind, mounted for adjustment on the body 1, longitudinally of the body. The bracket includes a wing 10 having an opening 11, the opening being shaped in any desired way, to accommodate one end or the other of a window shade roller. The bracket 9 includes a base 12, disposed at right angles to the wing 10 and mounted to slide on the outer surfaces of the flanges 6 of the body 1. At its free end, the base 12 of the bracket 9 has a pawl or lip 14 which may be either resilient or bendable, the pawl being adapted to engage in the seats 7 which are formed in the flanges 6 of the body 1. The base 12 of the bracket 9 has underlying fingers 15 engaged beneath the flanges 6 of the body 1. The fingers 15 are adapted to pass through the notches 4 when the bracket 9 is mounted on the body 1, and when the bracket is disengaged from the body.

In practical operation, the prongs 3 are driven into one end of the window frame 17, and then the prong 8 is driven into the outer surface of the frame 17, an operation 90 which will be understood readily when Figure 3 of the drawings is examined. The construction of the device is such that it can be mounted on the window frame and be removed therefrom without the use of screws, 95 nails or the like. The rib 5 serves to space the flanges 6 from the window frame 17, so that the underlying fingers 15 can slide between the flanges 6 and the window frame. The bracket 9 may be adjusted along the body 1 so as to accommodate window shade rollers of different lengths, the pawl 14 being engaged in the transverse seats 7.

It will be understood that any kind of a bracket may be used. Thus, in Figure 7 of the drawings, there is shown a bracket adapted to support a curtain rod. This bracket 16 may be used in place of the

bracket 9, and the device, therefore is equally efficient for supporting either a curtain or a shade wound on a roller.

Having thus described the invention,
5 what is claimed is:—

A window shade and curtain fixture comprising a body in the form of a plate, the constituent material of the body being distorted to form raised flanges along the 10 longitudinal edges of the body and to form an inwardly extended longitudinal rib located between the flanges, there being an inwardly extended prong struck from the rib and disposed approximately at right 15 angles to the rib, the body being supplied at one end with a flange disposed approximately at right angles to the body, the last-specified flange being provided with an inwardly extended prong disposed about at 20 right angles to the prong of the rib and about parallel to the rib, there being notches at the point of juncture between the body

and the last-specified flange, transverse seats being formed in the outer surfaces of the first-specified flanges; and a bracket comprising a wing and a base, the base being supplied at its free end with a pawl which is adapted to engage in the seats of the first-specified flanges, the base of the bracket being mounted to slide on the outer surfaces of the first-specified flanges of the body, the base having underlying fingers engaged beneath the first-specified flanges of the body, on opposite sides of the rib, the fingers being adapted to pass through the notches when the bracket is mounted on the body and when the bracket is disengaged from the body.

In testimony that we claim the foregoing as our own, we have hereto affixed our signatures.

EDWIN C. CURTIS.
GEORGE E. REYNOLDS.
